IRRADIATING MECHANICAL
REFRIGERATOR

Stewart C. Whitman, New York, N. Y.

Application October 22, 1932, Serial No. 639,142
Renewed June 15, 1936

9 Claims. (Cl. 99—247)

This invention relates to new and useful improvements in the art of mechanical refrigeration and more particularly to a therapeutic lamp to produce these results.

5 An object of this invention is to produce a lamp adapted to be mounted in a refrigerator to provide a continuously operated ultra-violet light source of beneficial wavelengths.

Another object of this invention is to produce 10 a convenient source of illumination for refrigerator interior.

A further object of the invention is to provide a refrigerator lamp of low heat dissipation.

Still another object of the invention is to provide a therapeutic lamp for refrigerators of a design which will irradiate the complete interior without sacrifice of storage space.

With these and other objects in view, my invention consists in the novel features of construction, combination, and arrangement of parts 20 as will be hereinafter referred to and more particularly pointed out in the specification and claims.

In the drawing forming a part of this application:

Figure 1 is a front view of my invention, partly in elevation and partly in section, showing it on an enlarged scale in relation to associated apparatus.

30 Figure 2 is a front elevation of the device with parts broken away, and

Figure 3 is a fragmentary horizontal section through the device taken on the line 3—3 of Figure 1, showing its position mounted with respect 35 to adjacent apparatus.

The above elements and their various arrangements will be more particularly described in the disclosure which follows.

A source of ultra-violet light in a refrigerator 40 possesses several meritorious features if properly designed. The interior of the storage chamber can be adequately illuminated, surface infection of foods can be arrested, odors eliminated, vitamin D produced in the irradiated food stuffs, and a generally wholesome and sanitary condition maintained.

The most important requirement in a lamp of this type is the frequency of the emitted light. 50 The lamp must not emit ultra-violet light of shorter wavelength than 2800 Angstrom units. If light of a higher frequency is radiated ozone is generated and the disagreeable odor is absorbed by the food stuffs affecting their flavor. 55 Further, high frequency ultra-violet light has a

destructive effect on organic substances and would result in rapid food spoilage.

Another important requirement is an economic one. The heat energy radiated from the light source must be extremely small, since the storage 5 chamber is well insulated and any appreciable heat generated would seriously affect the refrigeration and result in greatly increased power cost.

The lamp should be designed and mounted so that all portions of the storage space are irradiated equally. This condition requires a continual light source running the entire height of the chamber.

The present invention provides a lamp which satisfactorily meets all these conditions. 15

Referring to the drawing Figure 1 illustrates a refrigerator 1 containing the storage space 2, provided with shelves 3 and 4, and the refrigerating unit chamber 5. A compressor 6 is shown. The driving motor is not shown but the power 20 line is designated by the numeral 7 and a main switch by 8. The lamp is shown at 10. It is of the high voltage gas discharge type, containing a mixture of mercury vapor and a rare gas, as for example, argon at low pressure of the order 25 of 1 mm. of mercury. The tube as shown in the drawing has been enlarged with respect to the storage chamber for the sake of clarity. Actually, the tubing is of the order of $\frac{5}{8}$ inch in diameter and the two legs are spaced from each other 30 about $\frac{1}{2}$ inch. The electrodes 11 and 12 are constructed in any known manner.

In a gas discharge tube of this type most of the voltage drop across the tube takes place immediately adjacent to the electrodes and consequently most of the heat is dissipated at those points. For this reason the tube is mounted so that the portions carrying the electrodes project through the wall of the storage chamber 2 into the lower chamber 5, as shown at 13 and 14. The 40 tube is supported on its upper end by the clamp 15 and is protected from breakage by the screen 16. As shown, the tube is mounted vertically transversely of the shelves in spaced relation thereto. The position of the tube and protecting screen is 45 clearly shown in Figure 3. The transformer 17 supplies the current to the tube through the connections 18 and 19. The transformer is supplied from the main line 7 through the wires 20 and 21, which are permanently connected to the main 50 refrigerator line whereby the lamp is continuously lighted as long as the refrigerator is connected for operation. I have disclosed an electrically operated refrigerator. It will be understood that where the device is used with other types of me- 55

chanical refrigerators a source of current must be supplied. The transformer is of the constant current high reactance type commonly used for gas discharge tube. I have found a current of .010 amperes to be sufficient for a tube of this type. For a tube 6 feet long a transformer consuming 20 watts is sufficient. Of these 20 watts less than one watt is dissipated as heat in the interior of the storage chamber. The rest is dissipated in the lower chamber where it has no effect. The glass used for the tube is compounded so as to entirely screen all light of wavelength shorter than 2800 Angstrom units.

Having thus described the invention what is claimed is:

1. In a mechanical refrigerator including a storage chamber, an elongated gas discharge tube formed of glass containing mercury vapor, said tube being composed of glass which will transmit substantially no radiation shorter than 2800 Angstrom units, said tube being arranged vertically of said chamber and extending substantially the full length thereof, the electrode portions of said tube being disposed outside of said storage chamber, and means outside of said chamber for activating said tube.
2. In an irradiating mechanical refrigerator, a heat-insulated storage chamber, a working chamber, means in said storage chamber for carrying material to be refrigerated and irradiated, a mechanical refrigerating system contained in said storage chamber and said working chamber, a gas discharge tube generating ultra-violet radiation having a long central portion inside said storage chamber extending adjacent said means and also having a plurality of terminal portions each provided with actuating electrodes, said tube being provided with means for suppressing substantially all radiation shorter than 2800 Angstrom units, said tube being mounted so that said central portion is inside said storage chamber and said terminal portions are outside said storage chamber, mechanical protective means within said storage chamber adjacent said tube for protecting said portion of said tube in said chamber from breakage, and means for applying actuating potential to the electrodes of said terminal portions.
3. In an irradiating mechanical refrigerator, a heat-insulated storage chamber, a working chamber, a plurality of substantially horizontal stationary treating shelves in said storage chamber for carrying material to be refrigerated and irradiated, a mechanical refrigerating system contained in said storage chamber and said working chamber, a stationary gas discharge tube generating ultra-violet radiation having a long central portion inside said storage chamber extending substantially vertically transversely of said shelves in spaced relation thereto and also having a plurality of terminal portions each provided with actuating electrodes, said tube being provided with means for suppressing substantially all radiation shorter than 2800 Angstrom units, said tube being mounted so that said central portion is inside said storage chamber and said terminal portions are outside said storage chamber, and means for applying actuating potential to the electrodes of said terminal portions.
4. In an irradiating mechanical refrigerator, a heat-insulated storage chamber, a working chamber, a heat-insulating partition separating said storage chamber from said working chamber, a plurality of substantially horizontal shelves in said storage chamber for carrying material to be

refrigerated and irradiated, a mechanical refrigerating system contained in said storage chamber and said working chamber, a gas discharge tube of U-shape generating ultra-violet radiation having a long central portion and a plurality of terminal portions each provided with actuating electrodes, said tube being provided with means for suppressing substantially all radiation shorter than 2800 Angstrom units, both legs of said tube being mounted to project through said partition between said storage chamber, and said working chamber, said long central portion of said U-shaped tube being mounted inside said storage chamber extending substantially vertically transversely of said shelves, and said terminal portions being mounted in said working chamber, and means in said working chamber for applying actuating potential to said electrodes of said terminal portions.

5. In an irradiating mechanical refrigerator, a heat-insulated storage chamber, a working chamber, means in said storage chamber for carrying material to be refrigerated and irradiated, a mechanical refrigerating system contained in said storage chamber and said working chamber, a gas discharge tube generating ultra-violet radiation having a long central portion inside said storage chamber extending adjacent said means and also having a plurality of terminal portions each provided with actuating electrodes, said tube being provided with means for suppressing substantially all radiation shorter than 2800 Angstrom units, said tube being mounted so that said central portion is inside said storage chamber and said terminal portions are outside said storage chamber and means for applying actuating potential to the electrodes of said terminal portions.

6. In an irradiating mechanical refrigerator, a heat-insulated storage chamber, a working chamber, a plurality of substantially horizontal stationary treating shelves in said storage chamber for carrying material to be refrigerated and irradiated, a mechanical refrigerating system contained in said storage chamber and said working chamber, a stationary gas discharge tube generating ultra-violet radiation having a long central portion inside said storage chamber extending substantially vertically transversely of said shelves and also having a plurality of terminal electrode portions each provided with actuating electrodes, said tube being provided with means for suppressing substantially all radiation shorter than 2800 Angstrom units, said tube being mounted so that said central portion is inside said storage chamber and said terminal electrode portions are outside said storage chamber, and means for applying actuating potential to the electrodes of said terminal portions.

7. In an irradiating mechanical refrigerator, a heat-insulated storage chamber, a working chamber, means in said storage chamber for carrying material to be refrigerated and irradiated, a mechanical refrigerating system contained in said storage chamber and said working chamber, a gas discharge tube generating ultra-violet radiation having a long central portion, inside said storage chamber extending adjacent said means and also having a plurality of terminal portions each provided with actuating electrodes, said tube being formed of glass which will obstruct substantially all radiation shorter than 2800 Angstrom units, said tube being mounted so that said central portion is inside said storage chamber and said terminal portions are outside said storage chamber, and means for applying actu-

ating potential to the electrodes of said terminal portions.

8. In an irradiating mechanical refrigerator, a heat-insulated storage chamber, a working chamber, a plurality of substantially horizontal stationary treating shelves in said storage chamber for carrying material to be refrigerated and irradiated, a mechanical refrigerating system contained in said storage chamber and said working chamber, a stationary gas discharge tube generating ultra-violet radiation having a long central portion inside said storage chamber extending substantially vertically transversely of said shelves and also having a plurality of terminal portions each provided with actuating electrodes, said tube being formed of glass which will obstruct substantially all radiation shorter than

2800 Angstrom units, said tube being mounted so that said central portion is inside said storage chamber and said terminal portions are outside said storage chamber, and means for applying actuating potential to the electrodes of said terminal portions. 5

9. In a refrigerator including a chamber, an elongated gas discharge tube formed of glass which will transmit substantially no radiation shorter than 2800 Angstrom units, said tube being arranged vertically of said chamber and extending substantially the full length thereof, the electrode portions of said tube being disposed outside of said chamber, and means outside of said chamber for activating said tube. 10 15
